UNITED STATES PATENT OFFICE

JOHN DEBLIEUX, OF OPELOUSAS, LOUISIANA

SIGNALING DEVICE FOR MOTOR VEHICLES

Application filed November 22, 1929, Serial No. 409,145, and in Canada January 24, 1930.

This invention relates to signaling devices to be used on motor vehicles to indicate to the drivers of other vehicles, the intended stopping, slowing or the intended direction of turning of the vehicle equipped with the device, and is more particularly concerned with a device of this character manually controlled by the vehicle operator and constructed and functioning to simulate the arm signals now practically standardized and in use in the majority of States.

These practically standardized arm signals provide for the extension of the arm outwardly from the side of the vehicle with the fore-arm bent upwardly at the elbow for right turns; with the arm extended horizontally for left turns; and with the arm bent downwardly from the horizontal for slowing or stopping.

20 The present invention provides an arm type signal having a fore-arm (and hand) section mounted for swinging movement relatively to an upper arm section and for swinging movement with said upper arm section, and manually operable means for controlling the movement of these sections. Since the signaling arm sections simulate the human arm, they will be described in terms thereof as the mechanical equivalents of the human arm structure.

30 The invention consists in the constructions, arrangements and combinations of parts hereinafter described and claimed and will be more clearly apparent from the following 35 detailed specification which is to be read in conjunction with the accompanying drawings forming part thereof and illustrating a preferable embodiment of the invention.

40 In these drawings:

Figure 1 is a fragmentary perspective view of a motor vehicle showing my signaling device applied thereto.

45 Figure 2 is a view in side elevation of the device, the signaling arm being drawn into

its casing and the vehicle cowl being shown in section.

Figure 3 is a transverse vertical section on an enlarged scale through arm and casing.

Figure 4 is a similar sectional view but with the upper and fore-arm sections swung outwardly from the casing to the signaling position shown in Figure 1.

Figure 5 is a transverse vertical section through the casing and signal arm of Figure 3, taken on line 5—5 of Figure 3.

Figure 6 is a transverse horizontal section through the pivot of the fore-arm section taken on line 6—6 of Figure 3.

Figure 7 is another transverse horizontal section including the pivot point of the upper arm section and taken on line 7—7 of Figure 3.

Figure 8 is a fragmentary view in elevation of the casing, showing the third rock shaft operating cam and abutment arm in full lines in the withdrawn position of the signal arm within the casing, with the position of the cam in the first signaling position of Figures 1 and 4 shown in dotted lines.

The device of the present invention is attached to the side of the vehicle body adjacent and forwardly of the operator or driver and provides a signal arm conforming to the elements of the human arm and positioned correspondingly in giving traffic signals so that in the following description and claims, the elements of the signal arm are described in corresponding terms as the mechanical equivalents of the human arm structure.

The device is carried in an elongated relatively narrow box-like casing 1 having an open outer side and which is secured as shown in Figure 1 by means of brackets 2, or equivalent attaching means, to the frame post 3 of the wind shield, or to the corresponding part of the vehicle body, with its open side outermost. The casing 1 may be of any suitable material and is designed to house the

signal arm in its inoperative or non-signaling position.

This signal arm comprises an upper arm section 4 and a fore-arm section 5 which may have its outer end formed to simulate the human hand as indicated at 6 in Figure 1. The upper arm section 4, as shown, is in the form of a flat tubular body of metal or other suitable substance, open at its opposite ends, and pivotally mounted at what may be termed its shoulder end, or that point conforming to the shoulder joint of the human arm, on a rock shaft 7 traversing the casing 1 adjacent its lower outer edge. A sleeve 8 spanning the interior of the tubular arm section 5 and rigid therewith receives rock shaft 7 and is suitably fixed thereto as, for example, by the pin shown in Figure 3 so that rocking of the shaft will cause the sleeve and the attached arm section 4 to swing. The rock shaft 7 is extended outwardly from the casing 1 in the direction of the vehicle operator as shown clearly in Figure 5 and mounts thereon certain operating means hereinafter described. This shaft therefore constitutes the shoulder joint or pivot of the signaling arm.

At its other and outer end, the upper arm section 4 has its vertical side faces formed on the curve of a circle and between said curved ends is cut away to an extent approximating a semi-circle to receive the lower or elbow end of the fore-arm section 5.

This fore-arm section 5 is, as shown, in the form of a flat tubular member of a thickness to fit between the sides of the casing 1 and of less thickness than the upper arm section 4 to fit in the cut out open end thereof. Its lower end has its vertical side faces curved on the contour of a circle corresponding to that of the upper arm section, the metal or other material spanning the ends of these vertical side faces being cut out to provide clearance for certain spring connections later described, a portion of this connecting surface indicated at 9 in Figure 4 being inset from and concentric with the curved end of the upper arm section 4 to extend within its curvature as a shield preventing the entrance of rain, etc. therein. A second rock shaft 10 traverses the lower end of the fore-arm section 5 axially of its semi-circularly contoured end and of that of the upper arm section 4 and is journaled in the sides of said upper arm section. Thus the fore-arm section is pivotally mounted upon the upper arm section at that point corresponding to the elbow joint of the human arm. In the aligned positions of the fore-arm and upper arm sections, a shoulder 11 formed at the junction of the inset shield portion 9 of the fore-arm with the side and shown in Figure 4, abuts the edge 12 of one of the connecting sides of the upper arm section. The end of the opposite connecting side is out-turned as at 13, Figure

4, to provide a stop for the adjacent connecting side of the fore-arm section when the latter is moved toward the vertical to a signaling position as later described, and as shown in the drawings in Figures 1 and 4.

Internally of the hollow fore-arm section 5 a sleeve 14 is mounted on the second rock shaft 10 and is pinned thereto, this sleeve carrying two oppositely disposed arms 15 and 16 which extend in the horizontal in the vertical non-signaling position of the arm sections shown in Figure 3. To the end of the inner arm 16 (in the position shown in Fig. 3) is anchored one end of a tensioned coil spring 17 whose opposite end is anchored to a bracket plate 18 suitably secured to the base of the casing 1 adjacent its inner end. Intermediate of the first rock shaft 7 and the bracket 18 a third rock shaft 10 traverses the casing 1 adjacent its base and is journaled therein, one end of this rock shaft extending outwardly from the face of the casing in the direction of the vehicle operator and mounting an abutment crank arm 20 thereon which in the vertically alined non-signaling position of the arm sections extends slightly inclined outwardly from the vertical as shown in Figures 6, 7 and 8. The edges of the sides of the upper arm section at the inner end of said section are notched as shown at 21 in Figure 4 to clear the rock shaft 19.

This rock shaft within the casing 1 is provided with a sleeve 22 clamped thereon and having an arm 23 extending outwardly therefrom and substantially alining with the abutment crank arm on the extended outer end of the rock shaft. The arm 23 is provided with an offset eye 24. A connector including a section of coil spring 24 and a section of chain links 25 interconnects the eye 24 with the end of the opposite arm 15 on the second rock shaft 10. This spring and link connection, 24-25, in the vertically alined position of the arm sections, shown in Fig. 3, is slack and not under tension and is overcome by the tension of the coil springs 17 anchoring the opposite arm 16 to the casing. Therefore, when the first rock shaft 7 is actuated to swing its attached upper arm section 5 outwardly from the casing 1, the tensioned coil spring 17 will act to turn the rock shaft 10 and swing the fore-arm section upwardly toward the vertical until the connecting side of the fore-arm section engages and is stopped by the abutment 13 with the fore-arm extended upwardly in the familiar "right turn" signaling position of the human hand. When this point has been reached, the slack in the spring-link connection 24-25 will be taken up and the latter connection will be substantially taut. Certain actuating means for the rock shaft 7 will be provided with position-indicating means so that the movement of the arms may be stopped at this position which will constitute the first signaling position of the arm 130

when out-swung from the casing 1. Further movement of the rock shaft 7 and its attached upper arm section 4 outwardly in the same direction is arranged to cause pull through the spring-link connection 24-25 to overcome the tension of the spring 17 and reversely to swing the fore-arm section into engagement with the upper arm section, bringing the stops 11 and 12 into engagement as the upper arm section swings downwardly from its position inclined upwardly from the horizontal of Figs. 1 and 4 to the horizontal representing a second signaling position designating a "left turn". When this point has been reached, the fore-arm and upper arm sections 5 and 4 will be in alinement and extend in the horizontal, in which position they are maintained by the tension applied through the spring-link connection 25 and rock shaft 19. This tension is secured as follows:

It will be seen from Figs. 6 and 8 of the drawings that the extended end of the first rock shaft 7 has clamped or otherwise fixedly secured thereto an arm 26 which in the vertical non-signaling position of the alined arm sections, extends vertically downward (Fig. 8) and has its lower end offset and formed as a cam 27 lying in the plane of the abutment crank arm 20 of the third shaft 19. Movement of the rock shaft 7 in a counter-clockwise direction as viewed in Figure 8 to swing the arm sections outwardly from the casing to the first signaling position shown in Fig. 4 will bring the cam 27 into abutting relation to the abutment crank arm 20 as indicated in dotted lines, Fig. 8. Further movement of the rock shaft in the same direction or from the position shown in Figs. 1 and 4 to a second signaling position with the arm sections 4 and 5 alined and in the horizontal, will cause the cam 27 to turn the crank arm 20 in a clockwise direction and similarly swing the internal arm 23 on rock shaft 19 to apply through the spring-link connection 24-25, pull against the second rock shaft 10 overcoming the tension of spring 17 and reversely moving rock shaft and the fore-arm section 5 from its position inclined upwardly to the horizontal shown in Figures 1 and 4 outwardly and downwardly into alinement with the upper arm section 4 until the abutments 11 and 12 (Figure 4) engage. The cam at this point will remain in engagement with the crank arm, maintaining the arm sections 5 in alinement while they are extended in the horizontal and during a further downward movement of the arm sections conjointly to a plane below the horizontal representing a third signaling position or the "slowing" or "stopping" signal at which point the cam 27 will still engage the crank arm 20 and resist reverse movement thereof through the tensioned spring 17. On reverse movement of the rock shaft 7, the cam will continue to maintain the arm sections in alinement as the

arm is swung from its lowermost signaling position back to the horizontal. As the arm sections are now further swung upwardly from the horizontal to the initial signaling position inclined upwardly from the horizontal, the cam 27 will begin to release the crank arm 20 and permit the tensioned coil spring 17 to swing the sleeve 14 and the fore-arm section relatively to the upper arm section and to the upwardly inclined positions shown in Figs. 1 and 4. On movement of the arm sections from this first signaling position to lie within the casing 1 in inoperative signaling position, the fore-arm section will be returned to the vertical; the hand 6 thereof engaging the back of the casing 1 and causing the fore-arm section to swing to the vertical position shown in Fig. 3, as the upper arm section 4 entering the casing now straightens out into vertical position.

Various operating connections for the rock shaft 7 may be utilized. As shown in Figs. 1, 2 and 8, the outer end of a transversely extending link 28 is affixed to the extended end of the rock shaft 7. To its inner end is pivotally attached and from it depends a vertically extending link 29 which as shown is guided through a vertical bore 30 in the cowl of the motor vehicle illustrated and is pivotally attached at its lower end to the outer arm 31 of a bell crank lever pivoted on a horizontal stud 32 affixed to the dash. From the end of the opposite arm 33 of the bell crank lever a link 34 depends to pivotally connect to the lower end of an operating hand lever 35 which may be pivoted intermediate its ends at 36 to a bracket plate 37 clamped to the steering column, for example, and having an arcuate upper edge 38 provided with a series of spaced position denoting notches 39 as suggested in Fig. 1. The upper end of the lever 35 extends above the arcuate edge 38 and may be provided with a lateral offset 40 providing an operating handle and with a suitable spring pressed locking dog 41 which may, for example, have its upper end laterally offset to underlie the handle offset 40 and provide a convenient means for releasing the dog from a position denoting notch 39 when the handle end 40 is grasped to operate the connections to the rock shaft 7 for signaling. The notches 39 may have associated therewith certain legends denoting the slowing or stopping signal position, the left turn position, the right turn position, and the off position. The described connections are merely suggestive of one manner in which the rock shaft 7 may be actuated and this showing together with the specific structural details of the signal device per se are intended as illustrative rather than restrictive of the invention whose structure is subject to modification and adaptation to suit different conditions of manufacture and use in consonance with the spirit of the

invention and the scope of the appended claims.

What I claim, therefore, and desire to secure by Letters Patent is:

- 5 1. A signaling device for vehicles comprising a fixed support, a rock shaft mounted thereon, a signal arm carried by said rock shaft comprising an upper arm section carried by and moving with said rock shaft and a fore-arm section pivotally mounted on 10 one end of said upper arm section and normally extended outwardly therefrom in alinement therewith, vehicle driver operable connections to said rock shaft for effecting determinate movements of said shaft and its alined arms from an inactive to successive 15 signaling positions of the arm, means operated by initial swinging movement of said rock shaft and upper arm section from inactive signaling position with the arm sections alined to a first signaling position to coincidently move the fore-arm and hand sections from its initially extended alined position relatively to the upper arm section to a determinate signaling position at an angle 20 thereto, and means operative by further movement of said rock shaft and upper arm section toward a successive signaling position for coincidently moving said fore-arm 25 section into alinement therewith.
- 30 2. A signaling device for vehicles comprising a fixed support, a sectional signal arm pivotally mounted thereon at its lower end for swinging movement outwardly from a substantially vertical section-aligned non-signaling position, said signal arm comprising an upper arm section pivoted at its shoulder end on said support and a fore-arm section pivoted at its elbow end to the elbow end of the upper arm section and normally extended outwardly therefrom in alinement therewith in vertical non-signaling position, vehicle driver operable means for determinately swinging said fore-arm section 35 with said upper arm section outwardly on its pivot to successive signaling positions, means operative by initial outswinging movement of the upper arm section to coincidently swing said fore-arm section on its pivot from a normally extended and alined position relatively to the upper arm section to a determinate signaling position at an angle thereto, and means operative by further outswinging movement of said upper arm section to a succeeding signaling position for coincidently moving and maintaining said fore-arm section into alinement therewith.
- 40 3. A signaling device for vehicles comprising a fixed support, a rock shaft journaled thereon, an arm signal carried by and swinging with said rock shaft outwardly from a non-signaling substantially vertical position to successive signaling positions, said arm signal comprising an upper section 45 mounted at its shoulder end on said rock

shaft for movement therewith and a fore-arm section pivoted at its elbow end to the elbow end of the upper arm section and normally alined therewith in vertical non-signaling position, vehicle driver operable connections to said rock shaft for effecting determinate movement thereof to swing its attached arm section to selectively predetermined signaling positions, means connecting the fore-arm section and said support operative upon initial swinging movement of the upper arm section from vertical non-signaling position to coincidently swing said fore-arm section on its elbow pivot relatively to and out of alinement with the upper arm section to a determinate signaling position, and means operative to reversely swing and maintain said fore-arm section in alinement with said upper arm section upon further movement of said section in the same direction toward a succeeding signaling position.

4. A signaling device for vehicles comprising a fixed vertically extending casing having an open outer side, a sectional signal arm mounted and housed therewith in substantially vertical non-signaling position, said signal arm comprising an upper arm section pivoted at its shoulder end to said casing, and a fore-arm section pivoted at its elbow end to the elbow end of the upper arm section and normally extended outwardly therefrom in alinement therewith in vertical non-signaling position within said casing, vehicle driver operable connections to said pivoted upper arm section for effecting determinate swinging movement thereof to selectively predetermined positions outwardly of the casing, means connecting the fore-arm section and said casing conditioned by initial outswinging movement of said upper arm section to a first signaling position to swing the fore-arm section upwardly toward the vertical and relatively to the upper arm section to a determinate signaling position at an angle thereto, and means operated by further swinging movement of the upper arm section in the same direction toward a second signaling position effective reversely and coincidently to swing said fore-arm section to aline with the upper arm section and to assume therewith another signaling position.

5. A signaling device for vehicles comprising a fixed vertically extending casing having an open outer side, a sectional signal arm mounted and housed therein in substantially vertical non-signaling position, said signal arm comprising an upper arm section pivoted at its shoulder end to said casing, and a fore-arm section pivoted at its elbow end to the elbow end of the upper arm section and normally extended outwardly therefrom in alinement therewith in vertical non-signaling position within said casing, vehicle driver operable connections to said pivoted upper arm section for effecting determinate swing-

ing movement of said arm sections to selectively predetermined signaling positions outwardly of the casing, means connecting the fore-arm section and said casing tensioned by outswinging movement of said upper arm to a signaling position inclined upwardly from the horizontal and effective to swing the fore-arm section upwardly toward the vertical and at an angle relatively to the upper arm section to assume therewith an initial determinate signaling position, and means operated by further swinging movement of said upper arm section in the same direction to successive signaling positions at and below the horizontal respectively, effective reversely to swing and maintain said fore-arm section against said tension to aline and maintain it in alinement with the upper arm section in said successive signaling positions at and below the horizontal.

6. A signaling device for vehicles comprising a fixed vertically extending casing having an open outer side, a rock shaft journaled in and traversing said casing and having an end extended outwardly therefrom, a sectional signal arm mounted on said rock shaft and housed within said casing in substantially vertical non-signaling position, said signal arm comprising an upper arm section fixedly mounted at its shoulder end on said rock shaft, and a fore-arm section pivotally mounted at its elbow end on a second rock shaft journaled in the elbow end of said upper arm section, oppositely disposed arms on said second rock shaft, a tensioned coiled spring anchored to one of said arms and to said casing and normally effective to maintain said upper and fore-arm sections in alinement in the vertical non-signaling position thereof within said casing, a third rock shaft journaled in said casing adjacent to the first rock shaft having an arm thereon internally of the casing and having one end extended outwardly from the casing and provided with an abutment crank arm thereon, a normally untensioned connection between the other of said oppositely disposed arms on the second rock shaft, and the internal arm of the third rock shaft, vehicle driver operable connections to said first rock shaft for effecting determinate rotatory movement of said shaft and swinging movement of the signal arm outwardly and inwardly of the casing, a cam carried by the extended end of said first rock shaft in alinement with and normally spaced from the abutment crank arm of the third rock shaft and positioned to engage said abutment crank arm, at the end of out-swinging movement of the first rock shaft and upper arm section to a first signaling position with said arm section inclined upwardly from the horizontal and effective upon subsequent movement of said rock shaft and arm toward the horizontal to turn said third rock shaft and through its

connection to the second rock shaft to turn said second rock shaft and fore-arm section against the tension of said spring to aline and hold the fore-arm and upper arm sections for conjoint signaling position in the horizontal, said tensioned spring functioning, upon initial out-swinging movement of the signal arm to its first signaling position, to swing the fore-arm section upwardly toward the vertical to a determinate first signaling position in conjunction with the out-swung upper arm section.
